J. S. PIERSON, OF BROOKLYN, NEW YORK.

Letters Patent No. 78,127, dated May 19, 1868.

IMPROVED MACHINE FOR CUTTING AND STAMPING SOAP.

The Schedule referred to in these Letters Patent and making part of the same.

TO ALL WHOM IT MAY CONCERN:

Be it known that I, J. S. Pierson, of Brooklyn, in the county of Kings, and State of New York, have invented a certain new and useful Improvement in Soap-Cutting and Stamping-Machines, of which the following is a full, clear, and exact description, reference being had to the accompanying drawing, forming part of this specification, and in which—

Figure 1 represents a plan of a soap-cutting and stamping-machine, constructed in accordance with my improvement.

Figure 2, a longitudinal sectional elevation of the same, and

Figure 3 a transverse section thereof.

Similar letters of reference indicate corresponding parts.

In machines, as heretofore constructed, for cutting and stamping soap, it has been customary to employ such a multiplicity of movements for cutting the slab up into bars, that the process has necessarily been a slow, expensive, and laborious one. The devices previously employed for the purpose have been a wire cutter operated by one motion, stamp by another, and table actuated by a pawl and ratchet, the same in their action cutting but one bar at a time, and this not as clean or regular at the edges as is desirable.

My invention consists, firstly, in a combination of fixed knives, preferably of a sloping character, for cutting the slab into short or long bars, by the feed or adjustment of the slab-table in the machine, and for trimming the edge of the slab, cross-knives for cutting and determining the width of the bars, and stamps for stamping them, in such manner as, that after the table with the soap on it has been adjusted to its place, and the slab thereby trimmed and cut according to the length of bars required, a downward movement of the stamps and cross-knives serves to complete the operation of cutting the slab into a series of bars, and stamping the latter.

Likewise, the invention includes a combination of fixed knives, of a sloping character, for trimming and dividing the slab into bar-lengths, and sliding slab-table, whereby the soap is prevented from rising, and from presenting a roughened appearance at the cut.

Also, the invention embraces such a combination of stamps and cross-knives as that the stamps are made to hold on or to bear down on the soap while the cross-knives are entering and receding, thereby insuring a smooth finish to the edges of the cut bars.

Referring to the accompanying drawing, A represents the stand or frame of the machine, carrying a bed, B, which may be provided with rails or guiding-strips, C, end-frame, D, and uprights, E E. The end-frame D is slotted for the adjustment on and along it of knives or cutters, F, which serve to trim the slab, and to divide it longitudinally in accordance with the lengths of bars required, as the slab, in the condition it is taken from the slabber, is fed through or on to the machine by a longitudinally-sliding table, G, provided with a back cross-strip or feeding-bar, a, said table, when slid to its place between the guide-rails C, with the soap lying on it, in front of the bar a, striking at its forward end a spring-lever or other suitable stop, H, which determines the position of the table and its slab of soap in the machine for stamping and dividing into proper widths of bars, the knives F, in or during the feed of the table G to its place on the bed B, having trimmed the rough edge of the slab, and cut or divided it longitudinally in accordance with the length of bar or bars required. There may be any number of such knives or cutters F, and the same be arranged at any suitable distance apart along the end-frame D, according to the required length of the bars or number of them in a line widthwise of the slab. Said knives slope or are bevelled downwards in a backwardly direction at their cutting-edge, whereby the soap, on being drawn or forced through or between them to effect its cut, by the feed of the table G to its place on the bed B against the stop H, is held or borne down by the knives, and a smooth edge or finish given to the upper surface of the cut, which would not be the case were the knives sloped in a reverse direction, or even made perpendicular at their cutting-edge to the table's travel.

I I are the stamps, on which any desired trade-mark may be made. These stamps run in direction of the width of the machine, and are arranged at a slight distance apart, forming, when united to a longitudinal beam,

J, and cross-beams, K, or other appropriate ties, a stamp-frame, which is supported or lifted, say, away from the soap by springs, L, arranged under the ends of the cross-beams K, or said frame may be otherwise equivalently raised and sustained.

To stamp the slab or bars into which the slab is being cut, it is only necessary to bring down the stamps on to the soap, which may be effected by a hand-lever, M, connected by a rod, b, with a second lever, N, arranged to cross and freely rest on the longitudinal beam J of the stamp-frame.

P P are vertical blades or cross-knives, formed of steel or metal strips, arranged to freely slide up and down between the stamps I I, and carried by an independent outer frame, R R R R, that is held up, and raised so as to free the knives of the soap, by springs, S, arranged under the corners of said frame, or said frame may be otherwise suitably lifted and sustained. These knives serve to divide the longitudinally-cut slab widthwise of it and determine the breadth of the bars. To effect the cut, they are or may be worked down into the soap by the treadle T, connected, by rods e e, with a swinging frame, U U, having its fulcrum as at d, and resting on arched braces, e, secured to the knife-frame R R R R.

It is desirable that the swinging frame U U should be adjustable in its connection with the treadle T, which may be done by nuts f f, arranged to screw on the rods e e; also, that the devices for operating the stamp-frame should be similarly adjustable by a nut, g, screwing on the rod b; likewise, that the knives P P should be made capable of being strained or set, as by screw-nuts h h at their opposite ends, or wrists carrying them.

The table G it is preferred to make of wood, or cover with some soft material, or else to provide it with cross-cuts or incisions, so that the knives P P, in being brought down, will fairly cut through the soap; also, to construct it with a longitudinal incision or incisions for the knife or knives F to similarly pass through the soap; and, furthermore, it is desirable that the devices, which serve to work the stamp and cross-knives frame, should be so hung or attached as to be readily removable, in order that said frames may be detached and others substituted in their places when it is required to change the width of the bars to be cut.

From this description, it will be evident that a slab of soap may be simultaneously cut into a large number of bars, and the same stamped, by simply feeding in the table G, then bringing down the stamps by depressing the lever M, and afterwards, and whilst holding down the stamps, depressing the treadle T to bring down the knives P P. This done, the foot may be relieved from the treadle T, and, after the knives P P are free of the soap, by the upward shooting of the frame which carries them, the lever M is released. This will leave the stamp-frame free to rise by the action of its sustaining-springs, when the spring stop-lever H may be drawn back to allow of the table of cut and stamper-bars being delivered at or through the back end of the machine, and which may be effected by feeding in, at the front or opposite end a succeeding table, with slab on it, for operation as before, thus keeping up a continuous feed; as it were, with only the necessary intermissions, which are very brief, to establish the cross-cutting and stamping of the slab, and which operations, including the drawing back of the table-stop H, may easily be performed by a single attendant, with or through his hands and foot.

In this way are the stamping and cutting up of soap into bars expedited and improved, and, in such connection, it may be observed that as the stamps hold down the soap while the cross-knives are both entering and receding to effect the severing of it into bars, a smooth and steady cut is secured, and the bars left with clean or regular edges, as also clean or regular ends, by the shape and action of the cutters that divide the slab longitudinally as it is fed or adjusted within the machine. The slab, cut as described, is represented by red lines in figs. 2 and 3.

What is here claimed, and desired to be secured by Letters Patent, is—

1. The combination of stationary knives F, sliding slab-table G, stamps I, and cross-knives P, for operation together, substantially as specified.
2. The cross-knives, frame, and stamp-frame, arranged independently of each other, in combination with devices for separately operating the same by foot and hand, as herein set forth, and whereby the slab may be held by the stamps while the cross-knives are entering and receding, essentially as described.
3. The combination of the knives F, made of a sloping character, as shown and described, and sliding slab-table G, for action in concert, as specified.

J. S. PIERSON.
